DESIGN FOR A SNOOD-HAT

Alexandre M. Grean, Mount Vernon, N. Y.

Application November 18, 1939, Serial No. 88,357

Term of patent 3½ years

To all whom it may concern:

Be it known that I, Alexandre M. Grean, a citizen of the United States of America, residing at Mount Vernon, county of Westchester, State of New York, have invented a new, original, and ornamental Design for a Snood-Hat, of which the following is a specification, reference being had to the accompanying drawing, forming part thereof.

In the drawing:

Fig. 1 is a side perspective view of a snood-hat showing my new design;

Fig. 2 is a rear view of the snood-hat shown in Fig. 1;

Fig. 3 is a side elevation of the snood-hat shown in Fig. 1, and

Fig. 4 is a top plan view of the snood-hat shown in Fig. 1.

I claim:

The ornamental design for a snood-hat, substantially as shown.

ALEXANDRE M. GREAN.
